M. E. H. POLTSCHBACH,
CORN WASHER,
APPLICATION FILED NOV. 15, 1916.

1,235,378.

Patented July 31, 1917.

UNITED STATES PATENT OFFICE.

MINNIE ELIZABETH H. POLTSCHBACH, OF SAN MIGUEL DE TUCURN, GUATEMALA.

CORN-WASHER.

1,235,378.

Specification of Letters Patent. Patented July 31, 1917.

Application filed November 15, 1916. Serial No. 131,435.

To all whom it may concern:

Be it known that I, MINNIE ELIZABETH H. POLTSCHBACH, a citizen of the Republic of Guatemala, residing at San Miguel de Tucurn, Republic of Guatemala, Central America, have invented certain new and useful Improvements in Corn-Washers; and I do hereby declare the following to be a full, clear, and exact description of the invention, 10 such as will enable others skilled in the art to which it appertains to make and use the same.

This invention relates to a corn washer and more particularly to a device especially 15 adapted for thoroughly washing hulled corn after it is boiled in ashes or lime preparatory to making tortillas therefrom.

An object of this invention is to provide 20 a perforated cylinder for receiving the corn and having an agitator therein for thoroughly washing the corn and loosening the shells from the kernels.

Another object of this invention is to provide a concave top having perforations 25 therein, whereby water may be poured into the cylinder while rotating the agitator to thoroughly soak and wash the corn.

A further object of this invention is to provide an inner cylinder adapted to slide 30 within the perforated cylinder for retarding the outflow of water therefrom so that the corn may be thoroughly washed and whereby the inner cylinder may be removed to allow the water to pass rapidly from the per- 35 forated cylinder when desired.

A still further object of this invention is 40 the provision of a corn washer of the above stated character, which shall be simple, durable and efficient, and which may be manufactured and sold at a comparatively low cost.

With these and other objects in view as will become more apparent as the description proceeds, the invention consists in cer- 45 tain novel features of construction, combination and arrangement of parts as will be hereinafter more fully described and claimed.

For a complete understanding of my in- 50 vention, reference is to be had to the following description and accompanying drawing, in which:

Figure 1 is a side elevation of the corn

washer constructed in accordance with my invention, 55

Fig. 2 is a vertical sectional view of the same,

Fig. 3 is a transverse sectional view taken on the line 3—3 of Fig. 1, and

Fig. 4 is a fragmentary vertical sectional view of a modified form of operating means for the agitator.

Referring in detail to the drawing, the numeral 1 indicates a perforated cylinder having its lower end closed by a bottom wall 2 which has a plurality of perforations 3 and a central boss 4 for receiving the lower end of an agitator 5. The agitator consists of a vertical rod having its lower end reduced to be received by the boss 4 and having a plurality of arms 6 secured thereto and arranged in staggered relation. The upper end of the vertical rod of the agitator 5 is reduced as illustrated at 7 and extends through a concaved cover 8 which has a plurality of 75 perforations 9 therein. A suitable handle 10 is secured to the reduced end 7 of the agitator 5 for rotating the agitator within the perforated cylinder 1. The cover 8 has a downwardly depending flange 11 for an 80 engagement with the upper edge of the perforated cylinder 1.

A pair of inter-crossing strips 12 are positioned upon the bottom 2 and have each end bent back upon itself to form foot rests 85 13, the ends of which are bolted or otherwise secured to the flange 14 formed on the bottom 2.

A cylinder 15 is slidably mounted within the perforated cylinder 1 for closing the 90 perforations within the cylinder 1 as clearly illustrated in Fig. 2.

In operation, the handle 10 is removed from the agitator and the cover 8 is removed from the perforated cylinder 1. Hulled 95 corn is then placed within the perforated cylinder 1 and the cover is later replaced thereon and the handle 10 is connected to the agitator. By pouring water within the concave cover 8, the water passes through 100 the perforations 9 into the perforated cylinder 1 and is prevented from passing out of the sides of the perforated cylinder by the inner cylinder 15. By rotating the agitator by the handle 10, the corn is thoroughly washed and soaked, the water with- 105

in the perforated cylinder 1 gradually passing out through the perforated bottom. After the corn has become thoroughly washed and soaked so that the shell of the 5 corn becomes loosened from the kernel, the cylinder 15 is removed from the perforated cylinder thereby allowing the water within the perforated cylinder to pass rapidly out through the side thereof. When rotating the agitator, the operator places his feet upon the foot rests 13 thereby holding the device against accidental movement.

Referring to my modified form of means for rotating the agitator as illustrated in 15 Fig. 4, a pair of bearings 16 are secured to the concave cover 8 and has journaled therein a shaft 17 to which is secured at one end thereof a crank handle 18. A beveled gear 19 is secured to the other end of 20 the shaft 17 and is in mesh with a beveled gear 20 carried upon the reduced end 7 of the agitator 5, whereby upon rotation of the crank handle 18, the shaft 17 will be rotated, rotating the agitator 5 through the beveled 25 gears 19 and 20.

While I have shown and described the preferred embodiment of my invention, it will be understood that minor changes in construction, combination and arrangement

of parts may be made without departing 30 from the spirit and scope of the invention as claimed.

Having thus described my invention, what I claim is:—

A corn washer comprising a perforated 35 cylinder, a perforated bottom closing one end of said cylinder, a perforated cover closing the other end of said cylinder, an agitator journaled in the cover and bottom, said cover being concave to form a pocket 40 for receiving water and permitting it to pass in the cylinder to wash corn therein, a solid cylinder located in the perforated cylinder for closing the perforations therein to compel the water to run from the 45 cover through the corn and out of the bottom, said solid cylinder adapted to be raised upwardly in the perforated cylinder to permit the water to drain quickly through the perforated cylinder, and means 50 for rotating the agitator.

In testimony whereof I affix my signature in presence of two witnesses.

MINNIE ELIZABETH H. POLTSCHBACH.
